SLIDING VEHICLE

Allen W. Berglund, 865 N. Howell St.,
St. Paul, Minn. 55104

Filed Mar. 6, 1968, Ser. No. 10,871

Term of patent 7 years

Int. Cl. D12—13; D21—03

U.S. Cl. D34—15

FIG. 1 is a perspective drawing of a sliding vehicle.
FIG. 2 is a front elevational view of the vehicle of FIG. 1.

FIG. 3 is a side elevational view of the vehicle of FIG. 1.

FIG. 4 is a rear elevational view of the vehicle of FIG. 1.

FIG. 5 is a bottom plan view of the vehicle of FIG. 1.

FIG. 6 is a sectional top plan view of the vehicle of FIG. 1 taken along section line 6—6 on FIG. 3.

FIG. 7 is a sectional view of the vehicle of FIG. 1 taken along section line 7—7 on FIG. 3.

I claim:
The ornamental design for a sliding vehicle, as shown.
